**METHOD AND MEANS FOR TRAPPING PAINT
OVER-SPRAY**

Sheila Forshee, Detroit, Mich.

Application February 21, 1956, Serial No. 566,934

4 Claims. (Cl. 98—115)

This invention relates to the art of paint spraying and has particular reference to a method and means for trapping and disposing of the over spray, and this application may be considered a continuation in part of my co-pending application, Serial No. 459,040 filed September 29, 1954, now Patent No. 2,841,073.

In my said co-pending application Serial No. 459,040, I disclosed a certain form of apparatus for practicing my invention. I now desire to disclose a modified form of apparatus, with which my novel method or process may be practiced, and intend also to particularly describe and claim in this application the novel method or process, which is partially disclosed in the co-pending application.

It is one of the objects of this invention to generally improve the art of paint spraying, and to provide a method or process, which is very economical to practice, because it eliminates much of the apparatus previously needed in such operations. In my co-pending application Serial No. 459,040, I pointed out some of the advantages of my invention, over the wet bath or water curtain types of spray booths, previously employed. The apparatus which I now disclose is similar in some respects, to that previously disclosed, but I have simplified and modified it, so that the apparatus herein disclosed may be used with greater facility in practicing the novel method.

The object therefore of this invention is to disclose a dry method, as opposed to a wet method, of disposing of the excess paint in a spray booth.

Another object of the invention is to provide improved means for practicing the method.

A further object of the invention is to provide a paint spray booth, which has a comparatively thin wall of highly absorbent, readily disposable material.

Another object of the invention is to provide a paint spray booth which has a substantially vertical, progressively moveable, thin wall of highly absorbent, normally dry, non-woven, fabric material, positioned to absorb and trap all excess spray paint.

Another object of the invention is to provide a paint spray booth having a thin wall of highly absorbent material of the character indicated, with means for maintaining a fresh supply of such material, and means for facilitating the easy disposal of used portions of such material.

The foregoing and other objects and advantages of the invention will become more apparent as the description proceeds, reference being made from time to time to the accompanying drawings forming part of the within disclosure in which drawings:

Fig. 1 is a perspective view of a paint spray booth embodying the invention.

Fig. 2 is an enlarged perspective view of the booth illustrated in Fig. 1, with parts broken away to show the relation of other parts.

Fig. 3 is a side elevational view of the device illustrated in Fig. 1 with parts broken away and parts in section.

2

Fig. 4 is a section taken substantially on the line 4—4 of Fig. 3.

Referring now more particularly to the drawing, it will be understood that in the embodiment herein disclosed, the reference character 7 indicates, in general, the paint spray booth, which is preferably made in three sections, designated by the reference characters 8, 9 and 10. The section 8 consists of a pair of wings 11 and 12 and a canopy 13. The section 8 serves as a protective stall for the operator 14, who is using a paint spray gun 15, to paint an object 16.

The sections 8, 9 and 10 are all preferably made of light sheet metal material and are fabricated and secured together by any suitable means.

The section 9 has a top 17 and side walls 18 and 19, which serve as a housing for and means to support, the upper roll 20, on which is stored the material, from which the fabric curtain 21 is formed. The curtain 21 extends downwardly from the roll 20, to form the front wall of the section 9. The curtain 21 passes over an idler roll 22, and on to a collector roll 23, which is constructed and driven as hereinafter described. The section 9 is provided with hinged panels 24 and 25, so that access may be had to the rolls 20 and 23, for loading, un-loading and replacing the curtain material 21. The curtain wall 21, is preferably backed up with an expanded metal screen member 26, which is preferably welded to angle members 27 and 28 (Fig. 3), which serve to re-inforce and support the walls of the section 9.

The screen 26 is intended to re-inforce the material of the curtain 21, so that the curtain 21 may withstand the blast from the spray gun 15, and the current of air, which passes through the curtain 21, and may resist the pressure of any object which might be forced against it.

The roll 20 is carried on an axle 29, the ends of which ride in channel members 30, secured to the inside of the walls 18 and 19. The roll 22 is similarly supported.

The rolls 20 and 22 are readily installed, by causing the ends of their axles to be received in the channels 30.

They are removed by a reverse action.

The collector roll 23 consists of a tubular member 23A (Fig. 4), which is supported at either end on hubs 31 and 32, which are respectively secured to end plates 33 and 34. The hub 31 and plate 33 being rotatable about

a drive shaft 35, which extends through the side wall 18 and through a bearing member 19. The shaft 35 is driven by a sprocket 36 as hereinafter described. The hub 31 is splined on the shaft 35, so that it may slide to the left, against the pressure of the spring 37, and return whereby the member 23A may be moved out of, and into engagement with the hub 32, for installing and removing the collector roll. The hub 31 is provided with keys 38, which engage slots 39, formed in the ends of the tubular member 23A, so that the latter may be rotated by the drive shaft 35. The hub 32 and end plate 34 rotate on a stub shaft 40, which is welded or otherwise secured, as at 41, to a backing plate 42, which is secured to the inner face of the wall 19. A roller bearing 43 is preferably interposed between the stub shaft 40 and the hub 32. With this construction and arrangement it is easy to discard the accumulated curtain material 21A, after it has been used and collected on the collector roll 23 by severing the curtain just above the roll 23 and removing the roll 23.

The sprocket 36 which rotates the shaft 35, is driven by a chain 44, which in turn is driven by a smaller sprocket 45, which is driven by an electric motor 46, through a suitable gear reduction, not shown. The drive motor 46 is preferably manually controlled, by means of a switch within easy reach of the operator 14, so that portions of the curtain material 21 may be intermittently advanced from the roll 20 to the collector roll 23.

The sprockets 36 and 45 and the chain 44, are all covered by means of a cover 47, which is secured by any suitable means, to the outside of the wall 18.

The motor 46 and its gear reduction are housed in the bottom of the section 10. The interior of the section 10, communicates at the top with a stack 48, in which is mounted an exhaust fan, not shown, which is driven by means of an electric motor 49. The exhaust fan draws a continuous stream of fresh air through the three sections 8, 9 and 10, and through the fabric curtain 21, 10 and out the stack 48, as indicated by the arrows in Fig. 3.

I will now describe in detail the material of which the curtain 21 is made. The curtain 21 preferably consists of a pre-determined length, of one hundred percent, non-woven, cotton fibres, having a high factor of absorbency, which fibers are calendered, or pressed, to a layer thickness of approximately one sixty-fourth of an inch, to provide a normally dry, smooth surface, without nap. As currently defined by the industry, non-woven fabrics are mats of fibers held together with a bonding material, or by the action of thermo-plastic and thermo-setting resins, mixed in with the fibers. No yarns or conventional weaving equipment is used. Non-woven, or bonded fiber fabrics, consist of fibers adhesively bonded to one another. The fibers are bonded together with heat, pressure and/or vacuum, subjected to various forms of applications, to insure uniform dispersion of the bonding agents. Bonded fiber fabrics are usually produced on conventional carding equipment as the basis for the web. The fibers in the carded web lie nearly parallel, giving greater strength in the warp wise direction. The fabric may also be produced on a garnetting machine. Bonding is done by a chemo-thermic process, under extremely high heat, pressure and/or vacuum.

The non-woven cloth referred to in this application is a blend of fibers, which will give maximum absorbency and is treated so that it will have a smooth surface without nap, with resins, which will add a maximum degree of bonding and tensile strength, and yet will offer little resistance to the passage of air therethrough. The fabric material is preferably flame-proofed, with any suitable chemical composition. The material so described, has a comparatively high tensile strength, offers little, if any, resistance to the passage of air there-through, and because of its high factor of absorbency, will catch, hold and absorb, any and all excess paint spray, which may contact it during a paint spray operation. This material when loaded with excess paint spray, is readily disposable. The used sections are continuously rolled onto the 45 collector roll 23, which when filled is removed and disposed of.

It is believed that the operation of the device will be understood from the foregoing description.

Although I have herein disclosed a certain embodiment of the invention, it will be understood that various modifications may be made in the practice of the invention.

tion, all of which are within the contemplation of the appended claims. So far as I am aware, no one has heretofore practiced, a dry method, of trapping and disposing of excess paint spray, by the utilization of such a material as hereinabove disclosed. One of the important features of this invention resides in the use of the material in the manner hereinabove indicated.

Having described my invention, what I claim and desire to secure by Letters Patent is:

1. The method of trapping and disposing of paint overspray, which consists of providing a booth-like structure having at least one moveable wall formed of a thin curtain of normally dry, highly absorbent, non-woven, cotton fabric material of sufficient tensile strength to permit it to be pulled from a rotating support, positioning an object to be paint sprayed in close proximity to said curtain, passing a current of air about said object and through and around said curtain and while said air is in motion, directing a paint spray toward said object, and thus causing said curtain to be removed from its said original wall position.

2. An overspray curtain for a paint spray booth, comprising an approximately one sixty-fourth of an inch in thickness, layer of normally dry, non-woven, cotton fabric material, pressed to a smooth and napless finish, and treated to resist fire, and having sufficient tensile strength to permit it to be pulled from location to location.

3. A curtain as defined in claim 2, including rotating means for suspending said curtain in said booth and means for pulling sections of said curtain into and out of a predetermined position with respect to said booth.

4. A paint spray booth having a moveable wall, consisting of a continuous layer of normally dry, highly absorbent, flame-proofed, non-woven, cotton fabric material, approximately one sixty-fourth of an inch in thickness, and pressed to a napless, smooth finish and having sufficient tensile strength to support large paint laden sections thereof, means for adjustably supporting said layer, means for directing a current of air through and around said wall, means for moving said layer, and means for collecting portions of said layer, so moved.
